UNITED STATES PATENT OFFICE

DONALD S. BARROWS, OF ROCHESTER, NEW YORK, ASSIGNOR TO THE SYMINGTON COMPANY, OF NEW YORK, N. Y., A CORPORATION OF MARYLAND

STRIKING CASTING

Application filed November 14, 1925. Serial No. 69,098.

This invention relates to devices for use in connection with draft gear and more particularly to a preferably integral combined striking casting adapted for application to the ends of the car sills.

The principal object of my invention, generally considered, is the provision of a combined casting which is formed with portions serving, respectively, as a striking casting and coupler carrier iron, and provided with rearwardly extending ears for connection with the webs of associated center sills.

An object of my invention is the provision of a combined casting formed with coupler striking and carrier iron portions, and provided with rearwardly extending ears formed with slots therein serving for receiving an associated draft key and connected with the adjacent web portions of the center sills.

Another object of my invention is the provision of a combined casting for connection with the underframe of a car so as to embrace the adjacent ends of the center sills thereof, said casting being formed with rearwardly extending ears or webs preferably connected with the adjacent web portions of the center sills exteriorly thereof and slotted for the reception of associated draft keys.

A further object of my invention is the provision of an improved construction for car underframes especially at the end portions thereof involving the employment of a combined casting with portions serving, respectively, as a coupler striking casting and carrier iron, and provided with inwardly extending ears or webs connected to the adjacent ends of the associated center sills, and serving as the front portions of cheek plates for said sills, said casting also being provided with a substantially horizontal shelf or upper web portion extending inwardly from the coupler striking portion over the carrier iron portion beyond the

cheek plate portions of said casting and preferably connected with the associated center sills, cover plate and end sill of the car.

Other objects and advantages of the invention relating to the particular arrangement and combination of the various parts will become apparent as the description proceeds.

Referring to the drawings illustrating my invention, the scope whereof is defined by the appended claims:

Figure 1 is a plan view partially in horizontal section of a portion of a car underframe embodying principles of my invention.

Figure 2 is a vertical central longitudinal section of the embodiment of my invention shown in Figure 1.

Figure 3 is an end view partially in section on the line 3—3 of Figure 2.

Figures 4, 5, and 6, are views corresponding, respectively, with Figures 1, 2, and 3, but illustrating a modification of my invention.

Referring to the drawings in detail, like parts being designated by like reference characters and considering, first, the embodiment of my invention illustrated in Figures 1, 2, and 3, there is shown a combined casting 1 formed with a coupler striking portion 2, a coupler carrier iron or sill tie portion 3 and rearwardly extending ear or web portions 4 preferably lying on the outside of and adjacent to web portions 5 of center sills 6 of the car. The web portions 4 are preferably connected to the adjacent ends of the center sills 6 by a plurality of rivets 7 and are also preferably bifurcated or formed as upper and lower sections 8 and 9, respectively, leaving notches or rearwardly open slots 10 therebetween, said slots preferably registering with the slots 11 provided in the associated center sills 6 for the reception of a usual form of draft key 12. For reinforcing the slotted portions of the

center sill webs 5, the slotted portions of the webs or ears 4 of the combined casting are preferably formed with outwardly extending ribs or flange portions 13. It will be apparent that by virtue of the connection between webs or ears 4 and the adjacent web portions of the center sills which are preferably provided with slots extending to the ends thereof, the upper and lower portions of center sill webs 5 separated by the slots therein are securely tied together. As an additional connection between the lower web portions 9 of the combined casting 1 and the center sills 6, said web portions 9 are preferably formed with outstanding flange portions 14 overlying the lower flanges 15 of the center sills and connected thereto by rivets 16.

For reinforcing the slots 11 in the webs 5 of the center sills beyond the webs or ears 4 of the combined casting 1, cheek plates 17 are preferably provided and connected on the outside of the webs 5 of the center sills by a plurality of rivets 18. These cheek plates 17 are preferably formed with one or more slots 19 registering with the slot 11 in the center sill webs and framed or bordered by flange or rib portions 20, the outwardly extending sections of which correspond with the flange portions 13 around slotted portions of the webs 4 and serve as continuations thereof while the inwardly extending portions 21 engage the edges of the slotted portions 11 of the center sills and serve for properly positioning the cheek plates and providing a greater bearing area for the draft key 12. The flanges preferably continue to the front or open slotted ends of the cheek plates 17 to form, in effect, continuations of the flange portions 13.

The striking casting portion 2 of the combined casting 1 is preferably formed with an upright web portion 22 adapted for engagement with the horn of the coupler 23 upon sufficient rearward motion thereof and a lower inwardly extending web portion 24 overlying the shank of the coupler 23. The web 22 is preferably increased in thickness toward the longitudinal center line of the car or toward the intermediate portion of said web so as to reinforce the same and allow for wear between it and the coupler 23. Extending from the upper edge of the striking portion 22 and continued rearwardly below the sill cover plate 25 and end sill 26 is a shelf or web portion 27 which is preferably connected to the cover plate 25 and the end sill 26 by means of rivets 28. For bracing the web portions 22, 24, and 27, together, longitudinally extending web portions 29 are preferably provided, the rear portions of which preferably taper and gradually merge into the web 27. The web 27 forwardly of the end sill 26 preferably extends transversely beyond the center sills

6 and the overhanging portions 30 of which are preferably braced with respect to the web portions 4 by means of transversely extending substantially vertical rib or flange portions 31 preferably extending the full height of the casting. These flange portions 31 are in turn braced to the web portions 4 by triangular gusset portions 32 and the corresponding portion of the web 27.

For permitting the web 27 to extend without a break between the sides thereof over the ends of the center sills, said sills are preferably coped or cut away as indicated at 33 for receiving portions 30 of the combined casting. Preferably beginning at approximately the outer edge of the end sill 26, the web portion 27 is preferably decreased in width so as to lie wholly between the center sills 6 thereby avoiding extending the coped portions 33 of the center sills for any material distance beyond the end sill. This makes it possible to firmly connect said end sill and center sills while likewise providing for the secure connection between the combined casting 1, the cover plate 25, the end sill 26 and the center sills 6. The narrowed portion of the web 27 is preferably extended for a substantial distance to underlie the end sill 26 and, as will be apparent from a consideration of Figure 2 particularly, it preferably extends beyond the ears or web portions 4 of the casting.

The coupler carrier iron portion 3 of the combined casting is preferably U or channel-shape in cross section and formed with an upper web portion 34 and depending flange portions 35 on either side thereof, said web and flange portions being preferably braced together by means of a transversely extending web portion 36 and the corresponding portions of the webs 4 of the casting. Overlying the carrier iron portion 3, there is preferably provided a wear plate 37 in accordance with usual practice for directly receiving the wear between the carrier iron portion and the coupler 23.

The vertical edges of the opening 38 through the casting 1 for the reception of the stem of the coupler 23 are preferably reinforced by inwardly extending flanges or webs 39. In accordance with usual practice, the stem of the coupler 23, as well as the forward portions of the yoke 40, are supported in proper position between the center sills 6 by means of the key 12 extending through registering slots in the coupler and yoke and through the slots 10 in the combined casting, slots 19 in the cheek plates and the slots 11 in the center sills, as will be understood. The slots 11 in the center sills may be of sufficient length to accommodate another key (not shown) if desired, in accordance with usual practice and, if so formed, the cheek plates 17 will be correspondingly constructed.

Referring now particularly to the modification of my invention illustrated in Figures 4, 5, and 6, a combined casting 1^a is shown which may be substantially identical 5 in construction with the combined casting 1 of the previous embodiment except that the rearwardly extending ears or web portions 4^a are shorter and are not adapted for direct engagement with the associated draft key 10 12^a. It will be seen in this embodiment that only three rivets 7^a are employed for connecting each ear or web 4^a with the associated webs 5^a as contrasted with the five rivets through each web of the first modification. For this reason, although the upper 15 and lower portions 8^a and 9^a of the web 4^a leave slots 10^a therebetween adapted to receive the associated draft key 12^a, they are not provided with any portions for direct 20 engagement with said draft key corresponding to the portions 13 of the first embodiment. For this reason, the cheek plates 17^a must extend forward to approximately the ends of the slots 11^a in the center sills 6^a 25 and the flange portions 20^a and 21^a thereof preferably extend entirely around the associated draft key 12^a to provide area therefor and reinforce the slotted portions 11^a in the center sills. As in the previous embodiment, 30 however, the connection between the web portion 4^a and the webs 5^a of the center sills serves for rigidly tying together the adjacent bifurcated end portions of said center sills. The slots 11^a in said sills, as in the 35 previous embodiment, preferably extend clear to the ends thereof. This connection between the slotted portions of the center sills is further reinforced in the present instance by the cheek plates 17^a which are 40 preferably riveted to the webs of the center sills, as in the previous embodiment, by rivets 18^a and the rearwardly extending web or ear portions 4^a from the combined casting 1^a are preferably embraced and connected 45 between the webs 5^a of the center sills and the adjacent ends of the cheek plates 17^a, which ends, for the purpose, are preferably offset as indicated at 41. Except as specially described, the combined casting 50 1^a may be identical with the casting 1 of the first modification.

It will be apparent that by virtue of the aforescribed construction, I have provided a preferably integral casting formed with 55 portions serving as a coupler striking casting portion and coupler carrier iron and also having rearwardly extending portions for securely connecting said casting with the webs of the associated center sills and slotted 60 either for receiving the associated draft key or forming the forward portions of cheek plates for said draft key. The overall dimensions of the casting, however, are not increased by the provision of the slotted or 65 cheek plate forming extensions because the

upper shelf or web portion of the casting is continued beyond the extensions, for connection with the cover plate and end sill of the car.

Although I have disclosed certain embodiments of my invention, it will be understood that modifications may be made within the spirit and scope of the appended claims. In said claims the term "car" is used in its broad sense and includes all railway vehicles. 70 75

Having now described my invention, what I claim is:

1. In combination with the center sills, cover plate therefor, and end sill of a car, an integral casting comprising portions serving, respectively, as a striking casting and coupler carrier iron, and provided with rearwardly extending ears connected with the webs of said center sills and a substantially horizontal shelf portion extending rearwardly from over the carrier iron portion beyond said ears, the adjacent ends of the center sills at their upper portions being coped for the reception of portions of said shelf extending transversely beyond said sills, and a portion 80 85 of said shelf extending rearwardly between the sills and connected with the cover plate and end sill.

2. In combination with car center sills formed with web portions and upper and lower flanges, a combined casting comprising portions serving, respectively, as a striking casting and coupler carrier iron, and provided with rearwardly extending ears 90 95 connected with the webs of said center sills, the lower rearward portions of the ears adjacent the lower flanges of the center sills being formed with flange portions overlying said lower flanges and connected thereto.

3. In combination with car center sills 100 105 provided with draft key receiving slots, a combined casting comprising portions serving, respectively, as a striking casting and coupler carrier iron, and formed with rearwardly extending ears provided with slots registering with the slots in the center sills, associated cheek plate portions connected to said sills, portions of said ears being embraced between and connected to adjacent webs of the center sills and said 110 115 associated cheek plate portions for reinforcing the slotted portions thereof.

4. In combination with draft sills having slotted webs, a cover plate therefor and an associated end sill of a railway vehicle, cheek 120 125 plates connected to the outer surfaces of said webs for reinforcing the slotted portions, said cheek plates having forwardly open slots registering with portions of the slots in said webs, and an integral casting comprising portions serving respectively as a striking casting and a sill tie portion spaced below said striking portion and connected thereto by upright side portions to provide an aperture for receiving the stem of a cou- 130

pler, the side portions of said casting extending rearwardly and connected to the outer surfaces of the webs of the draft sills and bifurcated at the slots therein to provide rearwardly open slots completing the slots in said cheek plates and forming, in effect, the forward complementary portions of said plates, the upper parts of said side portions being connected by a shelf extending rearwardly from the striking portion, and the rear portion of said shelf being connected to the cover plate and end sill.

5. In railway draft rigging, in combination with center sills having slots therein for the reception of a draft key, cheek plates connected one to each sill on the outer faces thereof, said cheek plates being adapted to reinforce the rear ends of said slots, each of said cheek plates having an open-ended slot adapted to register with a portion of the slot in the adjacent sill, and a striking casting member formed with rearwardly extending integral side portions connected to the outer faces of said sills forwardly of said cheek plates, the said side portions having rearwardly open slots serving to complete the slots of said cheek plates, said side portions also reinforcing the forward ends of said slotted sills, and means for integrally connecting the lower portions of said striking casting member.

6. In railway draft rigging, in combination with sills having slots open at the ends of said sills and adapted for the reception of a draft key, cheek plates connected one to each sill on the outer faces thereof, said cheek plates reinforcing the rear ends of said slotted portions, said cheek plates having forwardly open slots registering with portions of the slots in the sills to which connected, and a striking casting member formed with rearwardly extending integral side portions connected to the outer faces of said sills forwardly of said cheek plates, the said side portions closing the open ends of the sill slots and having rearwardly open slots registering with portions of the sill slots and alined with and completing the slots of said cheek plates, said side portions also embracing and reinforcing the forward ends of said sills, and an integral tie portion connecting the lower ends of said side portions.

7. In railway draft rigging, in combination with draft sills having slotted webs, a cover plate therefor, cheek plates connected to the outer surfaces of said webs for reinforcing the slotted portions, said cheek plates having slots registering with portions of the slots in said webs, and an integral casting comprising portions serving respectively as a striking casting and a sill tie portion spaced below said striking portion and connected thereto by upright side portions providing an aperture adapted to re-

ceive a drawbar, the side portions of said casting extending rearwardly, connected to the outer surfaces of said webs, and bifurcated to provide slots registering with the slots in said webs and forming, in effect, complementary forward portions of said cheek plates, the upper parts of said casting being formed with a shelf extending rearwardly from the striking portion, the rear portions of said shelf being connected to said cover plate.

In testimony whereof I affix my signature.
DONALD S. BARROWS.
